UNITED STATES PATENT OFFICE.

EDWIN J. TOOF, OF NEW HAVEN, CONNECTICUT.

DESIGN FOR A CLAMP-HEAD FOR BICYCLE-SADDLES.

SPECIFICATION forming part of Design No. 26,620, dated February 9, 1897.

Application filed July 27, 1896. Serial No. 600,715. Term of patent 7 years.

To all whom it may concern:

Be it known that I, EDWIN J. TOOF, a citizen of the United States, and a resident of the city and county of New Haven, State of Connecticut, have invented and produced a new and original Design for a Bicycle-Saddle Clamp-Head, of which the following description, taken in connection with the drawings herewith accompanying, is a specification.

Referring to the drawings, Figure 1 represents a side elevation of a clamp-head, showing my design; and Fig. 2 represents a vertical cross-section through the center of the same.

The leading feature of my design consists in a circular disk shape face at opposite sides of the clamp-head, having a scalloped or ribbed face.

The opposite sides *a a* of the clamp-head appear in circular outline, as in Fig. 1, upon the face of which is a raised circularly-arranged rib *b*, extending around a central open space *c* and having a transversely ribbed or scalloped surface *d*.

The outline of the clamp-head when viewed from the ends thereof, as in Fig. 2, joins with the sides *a a* and discloses an opening between the latter, as shown.

What I claim is—

The design for a bicycle-saddle clamp-head as herein shown and described.

EDWIN J. TOOF.
